UNITED STATES PATENT OFFICE.

WILLIAM P. BETTENDORF, OF DAVENPORT, IOWA.

CAR-TRUCK.

No. 849,194.

Specification of Letters Patent.

Patented April 2, 1907.

Application filed June 22, 1904. Serial No. 213,662.

To all whom it may concern:

Be it known that I, WILLIAM P. BETTENDORF, a citizen of the United States, and a resident of Davenport, in the county of Scott and State of Iowa, have invented certain new and useful Improvements in Car-Trucks, of which the following is a full, clear, and exact description.

Heretofore car-trucks, particularly for freight-cars, have been made so that when assembling the parts thereof or when taking the same to pieces bolts and rivets had to be taken into account and inserted in the holes previously made for their reception and tightened or loosened and removed therefrom. The use of bolts and rivets not only increases the cost of the truck both as regards material and labor, but constitutes an element of weakness, because their use requires the making of holes and openings at points where the parts come in contact and are connected.

My invention is designed to build a truck complete, the parts of which are readily interlocked when being assembled, are securely and rigidly held in interlocked relation when in use, and can be easily separated and "knocked down" for repair or substitution of new parts or otherwise. This I accomplish by the means hereinafter fully described, and as particularly pointed out in the claims.

In the drawings, Figure 1 is a plan view of my improved truck, showing the central portion of the upper arch of one of the side frames broken away and exposing the adjacent end of the bolster. Fig. 2 is a side elevation thereof. Fig. 3 is a longitudinal vertical section of said truck, taken on dotted line 3 3, Fig. 1, looking in the direction indicated by the arrows. Fig. 4 is a transverse vertical section taken on dotted line 4 4, Fig. 1, intersecting the king-bolt opening and showing one side thereof broken away from the other with the bolster-springs and spring-plank removed and the bolster lowered and its end resting on the sill of the central bolster-opening of the adjacent side frame. Fig. 5 is a transverse vertical section taken on dotted line 5 5, Fig. 1, looking in the direction indicated by the arrows with the bolster and brake mechanism removed. Fig. 6 is a fragmentary view of the spring-plank, a top plan of one end thereof being illustrated.

In the drawings, A A represent side frames which are preferably, together with the journal-boxes a a at each end thereof, cast in one piece of metal and are with one exception constructed in other respects substantially similar to the side frames for car-trucks for which Letters Patent of the United States were granted to me October 6, 1903, and numbered 740,617. The exception alluded to consists in providing the laterally-flanged sill b of the bolster-opening of the side frames with a longitudinal groove c in its upper surface, preferably in the same plane as the web of the side frames. Connecting these side frames is a spring-plank B, the ends of which rest upon the sill of the bolster-opening in the same and are interlocked therewith by having a transverse projection or tenon d on its under side near each end, which are of such dimensions and are so located that when the plank B is in proper position they will enter grooves c. The ends of said plank, preferably that portion resting upon the sills of the bolster-openings of the side frames, are provided with a series of upwardly-projecting bosses e e, that are located in alignment with the axis of the bolster-springs C C. These bolster-springs C are confined between an upper and lower spring-seat D D, each of which consists of a suitable plate having centering bosses f f, made by depressing the metal on the sides of the plates opposite the springs, so as to provide concavities that will no matter which end of the springs is lowermost fit over the bosses e e of the spring-plank, and thereby be prevented from being displaced in a horizontal direction.

The central portion of the spring-seats D are provided with bosses g, that project from each seat toward the opposite one to an extent greater than the bosses e and are made by depressing the opposite side of the seats. These springs are before being placed under the bolster compressed to an extent sufficient to enable them to sustain the weight of the car-body without depression, and the spring-seats are secured together to retain said springs in such compressed condition by a bolt E. The ends of this bolt extend through suitable openings in the centers of the bosses g of the spring-seats and are headed, and when under the greater weight of the load carried by the car the springs are compressed the headed ends of the bolt have longitudinal play in the concavity of the said

- bosses *g*, whose depth is sufficient to accommodate any play of the bolt under any compression to which the springs may be subjected.
5. The ends of the bolster *F* extend through the bolster-openings of the side frames *A* and rest upon and are supported by the springs *C*. The vertical and transverse dimensions of the ends of the bolster are such that they 10 can enter and normally occupy the upper portion of the bolster-openings of the side frames, and said ends are provided with guide-blocks *i i*, suitably secured to the sides of the same in the usual manner, that engage 15 the upper portion of the guide-columns *j*, forming the sides of the bolster-opening. The lower portion of the guide-columns are recessed in the edges next the bolster-openings to form insets *k k*, which makes the 20 lower portion of said openings wider, so that upon the springs being removed from under the ends of the bolster and said bolster lowered until about in the position shown in the right-hand half of Fig. 4 of the drawings said 25 bolster can be shifted longitudinally and removed. In order to permit of the removal of the springs, the height of the bolster-opening must be such that with the bolster in 30 proper position there will be under ordinary conditions sufficient space between the top of the ends of the bolster and the upper arch of the side frame to permit the bolster to be raised off said springs and the latter removed from under the ends thereof.
35. After the spring-plank, the bolster-springs, and the bolster have been removed from the truck the side frames are lifted slightly, so as to permit of the removal of the journal-bearings *G* from off the journals of the axle *H* and 40 out of the journal-boxes *a*, whereupon the side frames, which before were keyed to the axle by said bearings *G*, can be removed.
- Projecting inward from the upper arch of the side frames above the guide-columns are 45 studs *I I*, and journaled upon these studs are links or hangers *J J*, whose lower ends are attached to and support the brake-shoe heads *K*, which, as shown, are secured to the ends of and are connected by the brake-beam 50 *L*. In assembling the parts of my improved truck the brake-shoe gear is the last thing to be installed in place; but when knocking down the truck it is the first thing to be removed.
55. What I claim as new is—
1. A car-truck comprising side frames, journal-boxes on the ends thereof, a spring-plank, a bolster, and bolster-springs, assembled and held together in proper relation without bolts or rivets.
  2. A car-truck comprising side frames, journal-boxes on the ends thereof, a spring-plank, a bolster, and bolster-springs, assembled and removably held together in proper 65 relation without bolts or rivets.
3. A car-truck comprising cast-metal side frames, journal-boxes cast integral therewith, a spring-plank, a bolster, and bolster-springs assembled and held together in proper relation without bolts or rivets.
4. A car-truck comprising cast-metal side frames, journal-boxes cast integral therewith, a spring-plank, a bolster, and bolster-springs assembled and removably held together in proper relation without bolts or 70 rivets.
5. A car-truck comprising side frames, journal-boxes on the ends thereof, a spring-plank, a bolster, and bolster-springs, assembled and held together in proper relation by gravity without bolts or 75 rivets.
6. A car-truck comprising side frames, journal-boxes on the ends thereof, a spring-plank, a bolster, and bolster-springs, assembled and removably held together in proper 80 relation by gravity without bolts or rivets.
7. A car-truck comprising cast-metal side frames, journal-boxes cast integral therewith, a spring-plank, a bolster, and bolster-springs, assembled and removably held together in proper 85 relation by gravity without bolts or rivets.
8. A car-truck comprising cast-metal side frames, journal-boxes cast integral therewith, a spring-plank, a bolster, and bolster-springs assembled and removably held together in proper 90 relation by gravity without bolts or rivets.
9. A car-truck comprising a bolster, side frames having bolster-openings therein in which the bolster can be raised above its normal plane, bolster-springs supporting said bolster, a spring-plank the ends of which rest upon and interlock with the sills of said bolster-openings and upon which said springs are centered and sustained.
10. A car-truck comprising a bolster, side frames having bolster-openings therein in which the bolster can be raised above its normal plane, a spring-plank the ends of which 100 rest upon and removably interlock with the sills of said bolster-openings, normally compressed springs seated upon and removably interlocked with said spring-plank, and supporting said bolster.
11. A car-truck comprising a bolster, side frames having bolster-openings therein in which the bolster can be raised above its normal plane, a spring-plank the ends of which 105 rest upon and removably interlock with the sills of said bolster, bolster-springs, spring-seats between which said bolsters are retained in a normally compressed condition, the lowermost ones of which rests upon and interlocks with said spring-plank.
12. A car-truck comprising a bolster, side frames having bolster-openings therein in which the bolster can be raised above its normal position, and each of which have depressions in their sills, a spring-plank the ends of 110

which are provided with a downwardly-projecting protuberance engaging said depressions and are provided with upwardly-projecting bosses contiguous thereto, bolster-springs, spring-seats between which said bolsters are retained in a normally compressed condition, the lowermost one of which has concavities in its under surface which when said spring-seat rests upon the ends of said plank fit over and are engaged by said bosses.

13. A car-truck comprising a bolster, side frames having bolster-openings therein in which the bolster can be raised above its normal plane and below the normal plane of which said openings are made wider, bolster-springs supporting said bolster, a spring-plank the ends of which rest upon and interlock with the sills of said bolster-openings and upon which said springs are centered and sustained.

14. A car-truck comprising a bolster, side frames having bolster-openings therein in which the bolster can be raised above its normal plane and below the normal plane of which said openings are made wider, a spring-plank the ends of which rest upon and removably interlock with the sills of said bolster-openings, normally compressed springs seated upon and removably interlocked with said spring-plank, and supporting said bolster.

15. A car-truck comprising a bolster, side frames having bolster-openings therein in which the bolster can be raised above its normal plane and below the normal plane of which said openings are made wider, a spring-plank the ends of which rest upon and removably interlock with the sills of said bolster, bolster-springs, spring-seats between which said bolsters are retained in a normally compressed condition, the lowermost one of which rests upon and interlocks with said spring-plank.

16. A car-truck comprising a bolster, side frames having bolster-openings therein in which the bolster can be raised above its normal position and below the normal plane of which said openings are made wider, and each of which have depressions in their sills, a spring-plank the ends of which are provided with a downwardly-projecting protuberance engaging said depressions and are provided with upwardly-projecting bosses contiguous thereto, bolster-springs, spring-seats between which said bolsters are retained in a normally compressed condition, the lowermost one of which has concavities in its under surface which when said spring-seats rest upon the ends of said plank fit over and are engaged by said bosses.

17. A car-truck comprising side frames having no bolted or riveted connection one with the other, and each having a bolster-opening mediate its ends and journal-boxes secured to the ends thereof, a bolster the ends of which are removably supported on the

sills of said bolster-openings, and car-wheels the journals of the axles of which enter said journal-boxes and lock said side frames together without the aid of bolted or riveted parts.

18. A car-truck comprising side frames having no bolted or riveted connection one with the other, and each having a bolster-opening mediate its ends and journal-boxes immovably secured to the ends thereof, a bolster the ends of which are removably supported on the sills of said bolster-openings, and car-wheels the journals of the axles of which enter said journal-boxes and lock said side frames together without the aid of bolted or riveted parts.

19. A car-truck comprising side frames having no bolted or riveted connection one with the other, and each having a bolster-opening mediate its ends and journal-boxes cast in one piece therewith secured to the ends thereof, a bolster the ends of which are removably supported on the sills of said bolster-openings, and car-wheels the journals of the axles of which enter said journal-boxes and lock said side frames together without the aid of bolted or riveted parts.

20. A car-truck comprising side frames having no bolted or riveted connection one with the other, and each having a bolster-opening mediate its ends and journal-boxes secured to the ends thereof, a bolster and removable springs therefor, the ends of said bolster being removably supported on the sills of said bolster-openings, and car-wheels the journals of the axles of which enter said journal-boxes and lock said side frames together without the aid of bolted or riveted parts.

21. A car-truck comprising side frames having no bolted or riveted connection one with the other, and each having a bolster-opening mediate its ends and journal-boxes immovably secured to the ends thereof, a bolster and removable springs therefor, the ends of said bolster being removably supported on the sills of said bolster-openings, and car-wheels the journals of the axles of which enter said journal-boxes and lock said side frames together without the aid of bolted or riveted parts.

22. A car-truck comprising side frames having no bolted or riveted connection one with the other, and each having a bolster-opening mediate its ends and journal-boxes cast in one piece therewith secured to the ends thereof, a bolster and removable springs therefor, the ends of said bolster being removably supported on the sills of said bolster-openings, and car-wheels the journals of the axles of which enter said journal-boxes and lock said side frames together without the aid of bolted or riveted parts.

23. A car-truck comprising wheels, side frames, a spring-plank the ends of which

have gravity-retained interlocking connection with said side frames, and a bolster, said side frames being connected and retained in proper position by the axles of said wheels, 5 and having journal-boxes secured thereto, and with its boxes removable bodily in its entirety sidewise from the ends of said axles.

24. A car-truck comprising wheels, side frames, a spring-plank the ends of which have gravity-retained interlocking connection with said side frames, and a bolster, said side frames being connected and retained in proper position by the axles of said wheels, and having journal-boxes cast in one piece therewith secured thereto, and with its boxes removable bodily in its entirety sidewise from the ends of said axles.

25. A car-truck comprising wheels, side frames, a spring-plank the ends of which have gravity-retained interlocking connection with said side frames, a bolster, and removable springs therefor, said side frames being connected and retained in proper position by the axles of said wheels, and having journal-boxes secured thereto, and with its boxes removable bodily in its entirety sidewise from the ends of said axles.

26. A car-truck comprising wheels, side frames, a spring-plank the ends of which have gravity-retained interlocking connection with said side frames, a bolster, and removable springs therefor, said side frames being connected and retained in proper posi-

tion by the axles of said wheels, and having journal-boxes secured thereto, and with its boxes removable bodily in its entirety sidewise from the ends of said axles. 35

27. A car-truck comprising wheels, side frames, a spring-plank the ends of which have gravity-retained interlocking connection with said side frames, a bolster, and removable springs therefor, said side frames being connected and retained in proper position by the axles of said wheels, and having journal-boxes immovably secured thereto, 45 and with its boxes removable bodily in its entirety sidewise from the ends of said axles.

28. A car-truck comprising wheels, side frames, a spring-plank the ends of which have gravity-retained interlocking connection with said side frames, a bolster, and removable springs therefor, said side frames being connected and retained in proper position by the axles of said wheels, and having journal-boxes cast in one piece therewith secured thereto, and with its boxes removable bodily in its entirety sidewise from the ends of said axles. 55

In testimony whereof I have hereunto set my hand and seal this 18th day of June, 60 1904.

WILLIAM P. BETTENDORF. [L. S.]
